UNITED STATES PATENT OFFICE.

EDWARD L. McCLAIN, OF GREENFIELD, OHIO.

DESIGN FOR A SWEAT-PAD.

SPECIFICATION forming part of Design No. 28,576, dated May 10, 1898.

Application filed November 20, 1897. Serial No. 659,339. Term of patent 14 years.

To all whom it may concern:

Be it known that I, EDWARD L. McCLAIN, a citizen of the United States, residing at Greenfield, in the county of Highland and State of Ohio, have invented and produced a new and original Design for a Sweat-Pad; and I do hereby declare the following to be a full, clear, and exact description of the same, reference being had to the accompanying drawing, which forms a part of this specification.

In the annexed drawing, A represents a "sweat-pad," and B C are respectively its front and rear edges, which edges are pinked or notched, as shown.

I claim as my invention—

The design for a sweat-pad, as herein shown and described.

In testimony whereof I affix my signature in presence of two witnesses.

EDWARD L. McCLAIN.
